UNITED STATES PATENT OFFICE.

LOUIS JENSEN, OF CHICAGO, ILLINOIS, ASSIGNOR TO UNITED AUTOGRAPHIC REGISTER COMPANY, OF CHICAGO, ILLINOIS.

AUTOGRAPHIC REGISTER.

Application filed July 29, 1926. Serial No. 125,735.

My present invention relates to mechanism for moving or feeding apertured strip material and it has more particular reference to an autographic register and the means which 5 initially advance the strip or strips of material while the normal feed devices are engaged in the apertures and are therefore inoperative to feed the material. The latter means have become commercially known as 10 a "starter" or "restarter" and herein I have employed such designation to indicate the initial feed devices which are co-operatively related to one or more of the normal feed members of the autographic register.

The present structure embodies a sliding element mounted upon a rotatable body and said parts are actuated through the medium of certain of the normal feed mechanism and suitable gearing together with other instrumentalities that cause the sliding element to be projected away from the rotatable body prior to the time that the normal feed mechanism becomes inoperative upon the material so that the outer portion of said element 25 will be in engagement with the material and ready to initially advance the material upon the starting of the succeeding delivery operation.

One of the objects of the present invention 30 is to provide a starter device that is positively related to the normal feed members and is adapted to become effective or engaged with the material at a predetermined time in the operation of the register. Another object is to perform the above-mentioned 35 function in a dependable manner and with a structure that is sturdy and capable of withstanding the service to which it may be subjected. Other objects reside in providing a device of the above-mentioned 40 character that is novel in construction, simple in the arrangement of the parts, and economical to manufacture so that it will not increase the cost of the register, and also 45 may be installed upon registers of divers types. Further objects will be apparent after an understanding of my invention is had, and I herein refer to the accompanying drawings that disclose schematically a typical 50 or preferred manner of carrying out my invention and of accomplishing the divers objects thereof.

In the drawings:—

Figure 1 is a vertical end elevation of the 55 upper portion of the delivery or discharge

end of an autographic register showing the normal feed members and my improved starter devices in connection therewith.

Figure 2 is a fragmentary vertical section taken on line 2—2, Figure 1 looking in the 60 direction of the arrows, and diagrammatically illustrates the portion of the starter when in position to initially advance the material.

Figure 3 is a view similar to Figure 1, 65 showing the relative position of the starter when inoperative and during the advancement of the material by the normal feed members.

Figure 4 is an enlarged section longitudinally through the material engaging element 70 of the starter.

Figure 5 is an edge elevation of the parts shown in Figure 4 and drawn to the same 75 scale.

Figure 6 is a vertical section taken on the irregular line 6—6, Figure 1 and looking in the direction of the arrows to illustrate in elevation the control parts mounted upon the inner face of the register wall.

Figures 7 and 8 are schematic views in elevation of the control parts in two of their 80 positions during the operation of the feed devices.

Figure 9 is a schematic plan of a portion 85 of the apertured strip material such as it is preferred to use in this structure, the proportions of the strip being reduced.

The portion of the autographic register herein disclosed includes only the feed mechanism and consists of vertically disposed longitudinal side-walls 10 that are connected at their upper edges by a writing table or platen 11, said walls and platen forming the upper portion of a casing or housing in 90 which the supply of webs is stored in either roll or folded pad form. The webs each comprise a strip 12 (Fig. 9) that usually has tickets 13 or other matter printed thereon and between the tickets the webs are 95 punched to provide filing pin apertures 14 for convenience in storing the tickets and the like when they have been severed from the strip. The apertures are arranged in longitudinally disposed spaced rows so that 100 there is preferably a pair of apertures for each ticket.

At the discharge end of the platen is located the normal feed devices in the form of upper and lower opposed rollers, the former 110

being an elongated roller 15 the spindles at the ends of which are journaled in tubular bearing-posts 16 that arise from the upper longitudinal corners of the register casing 10 and one of said spindles has a gear 17 secured to it. The lower feed member is in the form of roller disks 18 mounted upon a drive spindle or shaft 19 that is journaled in the side-walls of the casing so that the 15 same is in vertical alinement with and disposed below the roller 15 and said spindle or shaft 19 has a gear 20 secured to it that is larger than gear 17 and meshes therewith. The disks 18 are spaced apart a 20 distance corresponding with the spacing of the longitudinal rows of apertures or perforations 14 in the strip, and as seen in the drawings the said disks are larger in diameter than the upper feed roller 15 in the same proportion as the large gear 20 is to the gear 17. Drive spindle or shaft 19 is rotated by means of a crank handle 21 secured to one of its ends that is extended through the casing wall and when said structure is operated the strip or strips of paper 25 will be advanced upon the platen 11 and discharged from the end of the apparatus until a set of perforations or apertures come into registry with the opposed peripheral portions of the upper and lower feed devices, whereupon the disks 18 will come into actual contact with the roller 15 through said apertures and further feed or advance of the strips will be stopped so that the discharged ticket or set of tickets may be torn off or severed from the strip or strips. 30

The starter mechanism, or parts which are adapted to engage the material to advance the latter while the normal feed members 40 are engaged in the apertures of the material and therefore inoperative to advance the same, are preferably mounted upon the rotatable drive shaft or spindle 19 that carries the normal feed roller disks 18. Secured upon the rotatable drive spindle or 45 shaft 19 intermediate the rollers 18 is a block 22 that is elongated in a direction transverse to said spindle, so that it projects radially from opposite sides thereof, and said block 50 has an automatically returnable presser-foot slidably mounted thereon. The presser-foot consists of a slide member 23 positioned against a face of said block and maintained thereon by headed screws 24 that pass through an elongated slot 25 in the slide and screw into the body of the block as shown in Figure 4 and said slot is enlarged or widened as at 26 (Fig. 2) to accommodate the spindle 19 and to permit the slide to reciprocate longitudinally upon the block without interference from said spindle. One end of the slide has a lateral portion 27 that extends over the end edge of the block to provide the presser-foot and has its outer surface 55 roughened to insure frictional contact with the strip material when the foot 27 is acting upon it. The opposite end of the slide has a lateral projection 28 that is adapted to be engaged by a cam element for moving the slide at the desired time, as will hereinafter 60 more fully appear. A spring 29, connected at one end to the block and at its opposite end to a pin 30 projecting from the slide, maintains the structure in the position shown in Figs. 4 and 5, wherein the presser-foot 27 is in contact with the adjacent end of the block and will not engage the strip material when the spindle 19 is rotated during the normal advance of the material through the instrumentality of the feed roller elements 15 and 18, but when the foot is moved away from the end of the block at the proper time its outer surfaces will be 65 in a position to engage the strip material between the same and the upper feed roller 15. 70

A rotatable shaft 31 is journaled in the side walls 10 of the register casing in a plane below the drive spindle 19 and said shaft is actuated by means of a large gear 32 secured thereto that meshes with a pinion 33 upon the adjacent portion of drive spindle 19 so that when the latter is rotated by the crank handle the difference in diameter between gears 32 and 33 will cause the shaft 75 to rotate at a slower speed than the drive spindle 19 in the ratio of one to three. Intermediate its ends the shaft 31 has a finger 34 secured to and projecting laterally from it and the outer portion of said finger has a rounded or cam-faced edge 35 and rotates 80 in the path of the projection 28 once to each three revolutions of the projection, so that when the slide and block have been rotated a predetermined number of times the cam portion will be in a position to engage the projection 28, thereby moving the slide in a direction to cause the presser-foot 27 to engage the material between its roughened surface and the upper feed roller 15. This 85 last described position is illustrated in Figs. 1 and 2 and 6 and the manner in which the cam clears the projection 28 is illustrated in detail in Figure 3. 90

The predetermined operation of the normal feed roller members, and consequently 95 the rotation of the presser-foot and its associated parts, is controlled by suitable devices that are automatically set during the operation of the apparatus to arrest the rotation of the crank-handle 21. This structure 100 comprises a bell-crank 36 fulcrumed on a pin 37 projecting from the outer face of the casing wall 10, which bell crank has one arm 38 extended upwardly and provided with a lateral stop 39 that is positioned in the path 105 of rotation of crank-handle 21 and at its upper end is provided with a lateral finger-piece 40, which the operator may press against to oscillate the bell-crank for 110 releasing the crank-handle. The opposite arm 115

120

125

130

41 of the bell-crank is provided with a lug 42 upon its outer end that operates in and passes through an elongated segmental slot 43 in the casing wall, and its end enters the 5 bifurcated end 44 of one of the arms of a second bell crank 45 fulcrumed upon a pivotal pin 46 upon the inner face of the casing wall. This latter bell-crank has an elongated arm 47 the end of which is provided with the bifurcation 44 heretofore mentioned, and said bell-crank is automatically returnable by means of a spring 48 that is secured at one of its ends to the casing wall and at its opposite end to a lateral member 10 15 15 49 extending from the hub of said bell-crank. The other arm 50 of this bell-crank is much shorter than its first mentioned arm 47, so that a slight movement of the outer end of arm 50 will move the bifurcated end 44 of 20 25 25 the other arm a greater distance. A cam in the form of a flange collar 51 is secured to and rotates with the shaft 31 and is engaged by the adjacent end of the short arm 50 of bell crank 45. This cam collar is concentric 30 35 35 with the shaft 31 through about two-thirds of its circumference and the remaining portion thereof is flattened as at 52, so as to cause a rocking or oscillation of bell-crank 45. The spring 48 maintains arm 50 of the bell-crank against the cam 51-52, so that when the flattened portion of the latter engages the end of arm 50 the bifurcated end 44 of the bell-crank will be lowered in order to return the other bell-crank 36 to its normal 40 45 45 position where the stop 39 will be in position to arrest the movement of crank-handle 21.

When the material has been advanced by the roller disks 18 and upper roller 15 until 40 the strip apertures register with the disk roller further feed of the material is arrested. At this point the cam edge 35 will have engaged the projection 28 and moved the presser-foot 27 toward the upper feed roller 45 15 with the paper strips between them. Further advancement of the paper strips, however, cannot be made at this time because the cam 51-52 has permitted bell-crank 45 to oscillate and move the stop 39 upon the other bell-crank 36 into the path and has arrested the rotation of the crank-handle. The discharged portions of the strips are torn off in the usual manner and after the next entry has been made upon the 50 55 55 succeeding ticket or set of tickets the operator grasps the crank-handle 21 and oscillates bell crank 36 by pushing against the finger-piece 40 to clear the stop from the path of the crank-handle and then rotates the latter. As soon as the mechanism begins to operate the presser-foot will advance the material a distance sufficient to disengage the roller disks 18 from the strip apertures. During this movement of the presser-foot the cam edge 35 is engaged with the pro-

jection 28, but after the roller disks 18 have cleared the apertures the cam edge disengages the projection and the presser-foot returns to normal position. Continued rotation of the crank-handle a predetermined 70 number of times advances the strips, and prior to the arresting of the rotation of the crank-handle the strip apertures will have registered with the roller disks 18 and the continued rotation of the crank-handle, 75 until automatically stopped, will not further advance the strips. During the numerous rotations of the elements mounted on drive shaft 19 there has been but one revolution of shaft 31 and therefore upon the final revolution of the first mentioned elements the cam edge will have reached a position where the projection 28 is engaged thereby and at this time the cam collar 51-52 will have oscillated the bell-cranks 45 and 36 so that the 80 85 stop 39 will arrest the movement of the crank-handle.

What I claim as new is:—

1. Devices for feeding strip material having longitudinal spaced apertures, comprising normal feed members that become ineffective to advance the material when engaged in the apertures, and a starter mechanism consisting of a rotatable element, and a reciprocable slide normally stationary on 90 said element and adapted to be moved outwardly on said element whereby to engage and initially advance the material when the normal feed members are ineffective.

2. Devices for feeding strip material having longitudinal spaced apertures, comprising normal feed members that become ineffective to advance the material when engaged in the apertures, and a starter mechanism consisting of a structure having a 100 movable member normally ineffective to advance the material and said member having a portion adapted to be elongated into engagement with the material to initially advance the latter.

3. Devices for feeding strip material having longitudinal spaced apertures, comprising normal feed members that become ineffective to advance the material when engaged in the apertures, and a starter mechanism consisting of a rotatable structure carrying a member ineffective normally to advance the material, and means for moving said member transverse to the axis of rotation of said structure for elongating said 110 structure whereby to engage the material and initially advance the latter.

4. Devices for feeding strip material having longitudinal spaced apertures, comprising normal feed members that become ineffective to advance the material when engaged in the apertures, a starter mechanism consisting of a structure having a movable member normally ineffective to advance the material, means for elongating a portion of 125 130

the movable member of said structure whereby to engage the material and initially advance the latter, and means for predeterminedly arresting the operation of the apparatus upon the elongation of said starter structure.

5. An initial feed or starter mechanism for autographic registers comprising a roller, a rotatable shaft, a transverse element secured on said shaft, and a reciprocable slide normally stationary upon said element and adapted to be moved outwardly on said element to engage the material between its outer edge and said roller whereby to initially advance the material when said roller is rotated.

6. An initial feed or starter mechanism for autographic registers comprising a roller, a rotatable shaft, a transverse element secured to said shaft, a reciprocable slide normally stationary upon said element, and means adapted to move said slide towards and into engagement with said roller whereby to initially advance the material when said roller is rotated.

7. An initial feed or starter mechanism for autographic registers comprising a roller, a rotatable shaft, a presser-foot secured to and rotatable with said shaft, and means for moving said presser-foot transversely of the shaft into operative relation with said roller whereby to initially advance the material therebetween.

8. In combination with the normal feed members of an autographic register, a presser-foot normally urged away from said members and adapted to be moved into engagement with one of said members to initially advance the material.

40 9. In combination with the normal feed members of an autographic register, a presser-foot normally out of engagement with said members, and means for moving said presser-foot into engagement with one of said members whereby to initially advance the material.

50 10. In combination with the normal feed members of an autographic register, a presser-foot normally urged away from said members, a cam for moving said presser-foot into engagement with one of said members, means for rotating said cam actuated by the normal feed members, and means for predeterminedly arresting the operation of the apparatus upon the engagement of the cam with said presser-foot.

55 11. In an autographic register normal feed members, a drive-shaft upon which one of said members is mounted, a normally in-

effective initial feed structure mounted on 60 said drive-shaft, a second shaft actuated by said drive-shaft at a predetermined ratio of speed, means on the second shaft for moving said initial feed structure into coercive relation to one of said normal feed members, 65 and devices actuated by the rotation of the second shaft to arrest the rotation of said drive-shaft.

12. In an autographic register normal feed members, a drive shaft on which one of the 70 said members is mounted, a presser-foot mounted on said drive-shaft and normally disengaged from the other feed member, a second shaft actuated at a predetermined ratio by said drive-shaft, means on said 75 second shaft for moving said presser-foot into engagement with one of said normal feed members, and devices actuated by the rotation of the second shaft to arrest the rotation of said drive-shaft.

13. In a starter for autographic registers, the combination with a normal feed roller, 80 of a rotatable body, a slide mounted thereon, a presser-foot upon one end of said slide, a projection on the opposite end of said slide, and a rotatable cam adapted to engage said projection and thereby move said presser-foot into engagement with said roller.

14. In a starter for autographic registers, 90 the combination with a normal feed roller, and a drive shaft upon which a coating roller member is mounted, of a body fixed to said shaft, a slide mounted on said body, a presser-foot carried by said slide, a rotatable driven-shaft having geared connection 95 with said drive shaft, and a cam on said driven-shaft adapted to move said slide and cause the presser-foot to engage said first mentioned feed roller.

15. In a starter for autographic registers, 100 the combination with opposed normal feed roller members, and a drive-shaft upon which one of said members is mounted, of a body fixed on said shaft, a slide carried by said body, a presser-foot on said slide, a rotatable 105 driven-shaft, a geared connection between said shafts whereby the driven-shaft is rotated at a slower speed than the drive-shaft, and a cam secured to said driven shaft and adapted to engage said slide during each 110 revolution of said driven-shaft and cause the presser-foot to engage one of said feed members.

Signed at Chicago, in the county of Cook 115 and State of Illinois, this 25th day of June, 1926.

LOUIS JENSEN.
